(57) **CLAIM**

The ornamental design of a node capsule for a seismic node, as described in the drawings.

DESCRIPTION

FIG. 1 is a left, front, top perspective view of a node capsule for a seismic node.

FIG. 2 is an additional left, front, top perspective view of the node capsule for a seismic node shown in FIG. 1.

FIG. 3 is a left, back, top perspective view of the node capsule for a seismic node shown in FIGS. 1 and 2.

FIG. 4 is an additional back perspective view of the node capsule for a seismic node as shown in FIGS. 1-3.

FIG. 5 is a left, front, bottom perspective view of the node capsule for a seismic node shown in FIGS. 1-4; and,

FIG. 6 is right, front, bottom perspective view of the node capsule for a seismic node shown in FIGS. 1-5.
